(57) **CLAIM**

The ornamental design for a personal watercraft front fascia, as shown and described.

DESCRIPTION

FIG. 1 is a perspective view taken from a front, right, top side of a personal watercraft front fascia according to our design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

Throughout the Figures, where shown, the dashed lines are included for the purpose of illustrating portions of the article which form no part of the claimed design.
